UNITED STATES PATENT OFFICE.

ROBERT H. WALLER, OF NASHVILLE, TENNESSEE, ASSIGNOR, BY MESNE ASSIGNMENTS, TO THE QUICKSAFE MANUFACTURING CORPORATION, OF NASHVILLE, TENNESSEE, A CORPORATION OF DELAWARE.

CAN OPENER.

Application filed December 7, 1922. Serial No. 605,395.

To all whom it may concern:

Be it known that I, ROBERT H. WALLER, a citizen of the United States, residing at Nashville, in the county of Davidson and 5 State of Tennessee, have invented a new and useful Improvement in Can Openers, of which the following is a specification.

This invention relates to can openers, and is designed particularly as an improvement 10 on the device shown and described in my co-pending application for patent on a can opener, filed May 17, 1922, Serial No. 561,651.

Objects of the invention consist in the 15 simplification of the construction so that it will be more compact and can be manufactured at a reduced cost, the elongated oscillating arm described and specifically claimed in some claims of my said co-pending application being eliminated in the specific form 20 of the invention particularly described herein. The present construction also provides simpler means for causing the penetration of the cutting wheel through the rim of a can 25 when the operating crank is turned in one direction, and for withdrawing said wheel from the can upon retrograde movement of the crank and thus allow the removal of the can. Other objects of the invention consist 30 in the provision of various combinations of parts and details of construction, desirable in an effective can opening device of the character referred to, all as will be more fully set forth in the accompanying description 35 and particularly set forth in the appended claims.

In the drawing, in which similar reference characters designate corresponding parts throughout the several figures:—

40 Fig. 1 is a perspective view of the improved can opener in operation;

Fig. 2 is an inverted plan view of the same;

45 Fig. 3 is a longitudinal sectional view of the device as viewed in Figure 1, the major portion of the can being broken away;

Fig. 4 is a top plan view showing the position of the parts after a retrograde movement of the operating crank to free the 50 cutter from the can and release the latter.

Referring to the drawing, there is illustrated a support consisting of a fixed base plate 1, preferably formed from heavy sheet

metal by cutting or stamping the same into oblong form having the corners thereof 55 preferably rounded, and adapted to be clamped to the edge of a table by means of a thumb screw 2, having threaded connection with the lower, horizontal arm 3, of a U-shaped bracket (4), formed also of heavy 60 sheet metal, preferably somewhat stouter than the base plate, and secured to the latter at one end of the same by means of rivets 5. The connecting arm 6 of the bracket, which is perpendicular to the base plate 1, is 65 located adjacent to the transverse center of the latter, so that the opposite end thereof overhangs the edge of the table, as clearly shown in Figures 1 and 3 of the drawing.

The thumb screw 2 carries at its upper end 70 a swiveled head 7, of inverted, saucer-shape to provide a peripheral contacting edge for engaging the lower face of the overhanging edge of the table, and the lower ends of the rivets 5 are formed into projecting tapered 75 heads 8, to impinge into the upper face of the table, and to coact with the said swiveled head to maintain the base plate rigidly in position when the screw is tightened.

As shown in Fig. 2 of the drawing, the 80 bracket 4 is arranged at one side of the longitudinal center line of the base plate, with one side edge of the same flush with one side edge of said base plate, though this specific arrangement is not obligatory.

85 An arcuate slot 9 is formed in the base plate between the arm 6 of the bracket and the outer, overhanging end of the said plate, the ends of the slot being rounded and spaced from the side edges of the plate.

90 Adjacent to the outer end of the base plate and in longitudinal alinement with one rounded end of the slot 9, there is provided an opening, forming a fixed bearing in which is mounted a revoluble spindle or stud 10, having secured to its upper end a spur gear 11 resting flat against the upper face of the base plate, the said spindle being free to rotate in either direction in its bearing, and having secured at its lower end a feed roller or wheel 12 whose upper face 95 preferably bears against the lower face of the base plate. The roller or wheel 12 is provided at its lower portion with an out-

100 standing annular flange 13, having its peripheral face milled to provide means for

engaging with and automatically rotating and feeding the can, in a manner to be described.

Slidably and revolvably mounted in the 5 arcuate slot 9 is another spindle or stud 14, which projects considerably above and below the upper and lower surfaces of the base plate respectively, and has secured at its upper end an operating crank handle 15, 10 which may be operated to turn said spindle in either direction. Between the crank handle 15 and the upper face of the base plate, there is interposed a spur gear 16 of equal diameter with the spur gear 11, and rigidly 15 secured to rotate with the spindle 14, while beneath the base plate the said spindle carries a feed roller 17 bearing against the lower face of the plate, the lower face of said roller being substantially in a horizontal 20 plane with the upper face of the milled flange 13, of the aforesaid wheel 12, as will be seen by reference to Figure 3 of the drawing.

The roller 17 is loosely mounted on the 25 spindle 14, and is free to rotate independently thereof, while a cutting disk 18 carried at the lower end of the spindle 14 is rigidly held to and forced to rotate therewith through the medium of a binding nut 19, 30 screwed to the lower threaded end 20 of the spindle, a spacing washer 21 being interposed between the nut and the lower face of the cutting disk 18, the said washer being of less diameter than the roller. 35 The two spindles or studs 10, 14 are substantially parallel to each other, while the slot 9 is arranged transversely to a line connecting the axes of said studs, when the cutting elements, i. e., the feed roller 12 and 40 the cutting disk 18, are in coacting position.

In operating the can opener, a can 24 having the usual circumferential flange 25 extending around the margin at either end, is introduced from below, the operating spindle 14 being moved to that end of the arcuate slot 9 farthest from the stationary spindle 10, such movement of the spindle 14 being caused by a counterclockwise movement of the crank 15, which causes the gear 50 55 60 65 70 75 80 9470 9475 9480 9485 9490 9495 9500 9505 9510 9515 9520 9525 9530 9535 9540 9545 9550 9555 9560 9565 9570 9575 9580 9585 9590 9595 9600 9605 9610 9615 9620 9625 9630 9635 9640 9645 9650 9655 9660 9665 9670 9675 9680 9685 9690 9695 9700 9705 9710 9715 9720 9725 9730 9735 9740 9745 9750 9755 9760 9765 9770 9775 9780 9785 9790 9795 9800 9805 9810 9815 9820 9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

vides ample space between the cutting edge 22 of the disk 18 and the milled edge of the flange 13 for the introduction of the flange 23 of the can 24, the lower face of the flange 13 bearing against the outer face 70 of the head 29 of the can, and the cutting edge 22 being in spaced relation to the side of the can and in horizontal alinement with the lower or inner face of the head 29.

By a reverse or clockwise movement of the 75 crank 15, the teeth of the gear 16 meshing with the teeth of the gear 11 and the stationary teeth 26, causes the spindle 14 to move along the slot 9 transversely of the base plate, when the edge 22 of the cutting disk is brought into engagement with and forced to penetrate the side of the can, and at the same time, and by the same movement, the roller 17 and the milled flange 13 are caused to clamp the outer and inner sides 85 of the flange or bead 25 of the can with sufficient force to cause the rotation of the can while the cutting disk is being rotated through the turning of the handle to bring about a complete severance of the entire 90 head of the can. During this operation it is only necessary to partially support the bottom of the can with one hand, while the other hand is turning the crank. It will be seen that the can opener may be used for opening cans of any size having the projecting flange which is generally found in all standard makes of cans.

It will be noted that the construction described enables certain advantageous effects to be secured even without the stationary rack or abutment comprising teeth 26, which is present in the preferred construction, as stated. Thus it will be noted that the movable stud is pressed against one end of its slot 9 during the can-cutting operation, by coaction of its gear 16 with the teeth of the coacting gear 11, the coacting parts being thus held in coacting relation. Also, that upon reverse rotation of the crank handle 110 the engagement of the two gears, as the teeth of one bear, as they rotate, against teeth of the other, causes a tendency for the movable stud to move along the slot until its gear is out of contact with the gear on the fixed stud. Hand lever or handle means attached to the movable stud can also be utilized for moving the stud 14 and cutter carried thereby lengthwise of the slot, by direct pressure thereon, one gear partially 115 rotating on the other during such movement, and if the toothed member 26 is present, partial rotation of gear 16 about the same will aid in removing it from engagement with gear 11.

From the foregoing, it will be seen that a simple, cheaply-manufactured and easily operated can opener has been provided, which may be quickly fastened in position on a table, and which may be readily oper- 120 125 130 135 140 145 150 155 160 165 170 175 180 185 190 195 200 205 210 215 220 225 230 235 240 245 250 255 260 265 270 275 280 285 290 295 300 305 310

ated by anyone without the danger of injuring the hands, or without the necessity for the expenditure of great force to operate the same, the simple action of turning the 5 crank serving to puncture or penetrate the can and cause the same to be rotated.

What is claimed is:

1. In a can opener, the combination of cooperating elements for cutting the can, comprising a rotary cutter and a roller for engagement with opposite surfaces of the bead of the can, parallel studs on which said elements are mounted, a fixed plate having a fixed bearing for one of said studs and having a slot transverse to the line connecting the axes of said studs when said elements are in coacting position, the other one of said studs being mounted directly in said slot for movement lengthwise thereof 15 and guided by the walls of said slot, gears on said studs adapted to mesh to drive one positively from the other, and a crank handle for rotating one of said studs, the stud in said slot being pressed against one end thereof by coaction of its gear with the coacting gear during operation of the device, the teeth of said coacting gear, upon reverse movement of said crank handle, bearing against the teeth of said first-named gear, 20 and thereby having a tendency to move the stud in said slot lengthwise thereof and carry one of said elements out of operative relation to the other element.
2. In a can opener, the combination of 35 cooperating elements for cutting the can, comprising a rotary cutter and a roller for engagement with opposite surfaces of the bead of the can, parallel studs on which said elements are mounted, a fixed plate having a fixed bearing for one of said studs and having a slot transverse to the line connecting the axes of said studs when said elements are in coacting position, the other one of said studs being mounted directly in said slot for movement lengthwise thereof, 40 and guided only by the walls of said slot, gears on said studs adapted to mesh to drive one positively from the other, and a crank handle on one of said movable studs 45 for rotating the same, said movable stud being pressed against one end thereof by coaction of its gear with the coacting gear during operation of the device, the teeth of said coacting gear, upon reverse movement 50 of said crank handle, bearing against the teeth of said first-named gear, and thereby having a tendency to move the stud in said slot lengthwise thereof and carry one of said elements out of operative relation to 55 the other element.
3. In a can opener, the combination of cooperating elements for cutting the can, comprising a rotary cutter and a roller for engagement with opposite surfaces of the bead 60 of the can, parallel studs on which said ele-
- ments are mounted, a fixed plate having a fixed bearing for one of said studs and having a slot transverse to the line connecting the axes of said studs when said elements are in coacting position, the other one of 70 said studs being mounted in said slot for movement lengthwise thereof, gears on said studs bearing against a face of said plate, adapted to mesh to drive one positively from the other, and a lever attached at one end 75 to said movable stud and having a manually engageable portion at its other end, the stud in said slot being pressed against one end thereof by coaction of its gear with the coacting gear upon forward rotation of said 80 cutter, the teeth of said coacting gear upon reverse rotation of said cutter, bearing against the teeth of said first-named gear, and thereby having a tendency to move the stud in said slot lengthwise thereof and carry 85 one of said elements out of operative relation to the other element.
4. In a can opener, the combination with a support having a slot, of a short spindle movably mounted in the slot, a rotary cutter carried by the lower end of the spindle, a feed roller on the spindle above said cutter and below the lower face of the support, a gear wheel on the spindle above the feed 90 roller and bearing against the upper face of the support, and a crank rigidly mounted on the upper end of the spindle, a second short spindle also mounted in the support 95 in spaced relation to the first-mentioned spindle and carrying a gear bearing against the upper face of the support and adapted to mesh with the first-mentioned gear wheel, a second feed roller mounted at the bottom of the second-mentioned spindle and below the lower face of the support, the feed rollers combining to engage the bead of a can 100 at the inner and outer sides thereof, and a fixed rack secured to the support at one side of the slot and in a position to be engaged by the gear wheel of the movable 105 spindle.
5. In a can opener, the combination with a support having a slot, of a short spindle movably mounted in the slot, a rotary cutter carried by the lower end of the spindle, a feed roller on the spindle above said cutter below the lower face of the support, a gear wheel on the spindle above the feed 110 roller and bearing against the upper face of the support, and a crank rigidly mounted on the upper end of the spindle, a second short spindle also mounted in the support 115 in spaced relation to the first-mentioned spindle and carrying a gear bearing against the upper face of the support and adapted to mesh with the first-mentioned gear wheel, a second feed roller mounted at the bottom of the second-mentioned spindle and below the lower face of the support, the feed rollers combining to engage the bead of a can 120 at the inner and outer sides thereof, and a fixed rack secured to the support at one side of the slot and in a position to be engaged by the gear wheel of the movable 125 spindle.
6. In a can opener, the combination with a support having a slot, of a short spindle movably mounted in the slot, a rotary cutter carried by the lower end of the spindle, a feed roller on the spindle above said cutter below the lower face of the support, a gear wheel on the spindle above the feed 130 roller and bearing against the upper face of the support, and a crank rigidly mounted on the upper end of the spindle, a second short spindle also mounted in the support in spaced relation to the first-mentioned spindle and carrying a gear bearing against the upper face of the support and adapted to mesh with the first-mentioned gear wheel, a second feed roller mounted at the bottom of the second-mentioned spindle and below the lower face of the support, the feed rollers combining to engage the bead of a can 135 at the inner and outer sides thereof, and a fixed rack secured to the support at one side of the slot and in a position to be engaged by the gear wheel of the movable spindle.

at the inner and outer sides thereof, and a fixed rack secured to the support at one side of the slot and in a position to be engaged by the gear wheel of the movable 5 spindle, whereby upon turning the handle in a clockwise direction, the spindle is moved through the slot so as to cause the gear wheel thereon to mesh with the other gear wheel, and upon moving the handle in 10 a counterclockwise direction, the gear wheel on the movable spindle is shifted from the gear on the other spindle and caused to engage the rack, thereby moving the cutter out of cooperative relation with the first- 15 mentioned feed roller so as to allow the insertion of the bead of a can between the cutter and said feed roller.

6. A can opener comprising a plate adapted to be secured to a table, coacting feed 20 rollers carried beneath the plate and bearing against the underside of the latter, one of said rollers being mounted on a revolute spindle which has a relatively fixed relation, the spindle of the other roller being 25 transversely movable on the base, a cutting disc carried by the last-named spindle below the support, spur gears mounted on the two spindles and bearing against the upper face of the support, a crank fixed to the movable 30 spindle for turning the same, stationary teeth mounted on the base adjacent to the gear on the first-mentioned spindle and adapted to be engaged by the teeth of the movable spur gear to cause the separation 35 of said feed rollers when the crank is turned in a counterclockwise direction, and to cause the feed rollers to clamp the bead of a can and to force the cutting disc through the side of said can and to sever the can top, 40 when the crank is turned in a clockwise direction.

7. A can opener comprising a substantially flat base plate, a clamp at one end of

the base plate, the remaining portion of the base plate being in overhanging relation, 45 the overhanging part of the base plate being provided with a curved slot, a revolute short spindle movably mounted in said slot, a gear wheel mounted on said spindle and bearing against the upper face of the 50 plate, an operating handle fixed to the upper end of the spindle above the gear wheel, a feed roller mounted on said spindle below the lower face of the base plate, a rotary cutter mounted on said spindle below 55 the roller, a loose spacing washer mounted on the spindle between the cutter and the roller, a second revolute short spindle spaced from the first-mentioned spindle and mounted in said plate in a relatively fixed 60 position, a gear wheel mounted on the second spindle and resting against the upper face of the plate, a feed roller mounted on said second spindle below the lower face of said plate and cooperating with the first-mentioned roller, and a fixed rack mounted 65 on the plate at one side of the second-mentioned gear wheel, whereby upon turning the handle in a clockwise direction, the gear wheel on the movable spindle is caused to 70 mesh with the gear wheel on the other spindle, and by turning the crank in a counterclockwise direction the gear wheel on the movable spindle is carried out of engagement with the other gear wheel and is 75 caused to engage with the teeth of the rack, at the same time separating the rotary cutter from the second-mentioned feed roller so as to allow the insertion of the bead of a can between the rotary cutter and said feed 80 roller.

In testimony, that I claim the foregoing as my own, I have hereto affixed my signature.

ROBERT H. WALLER.
